UNITED STATES PATENT OFFICE

2,529,608

UNLOADING ENDGATE FOR TRUCKS

Victor C. Hueneman, Garner, Iowa

Application March 30, 1948, Serial No. 17,971

5 Claims. (Cl. 214—82)

1

This invention relates to novel and useful improvements in devices for use in association with farm equipment.

An object of this invention is to unload wagons of its contents, particularly ensilage or other forage, to reduce the amount of manual labor involved.

Another object of this invention is to unload a wagon by improved means, the said means including an arrangement for increased mechanical advantage in moving a baffle or gate longitudinally of a wagon, thereby urging the contents of the wagon therefrom.

Another object of this invention is to provide a simplified device for unloading wagons which is inexpensive and which is smoothly operative.

Ancillary objects and features of novelty will become apparent to those skilled in the art, in following the description of the preferred forms of the present invention, illustrated in the accompanying drawings, wherein:

Figure 1 is a plan view of one form of the invention;

Figure 2 is a longitudinal sectional view taken substantially on the line 2—2 of Figure 1 and in the direction of the arrows, portions being shown in elevation;

Figure 3 is a pictorial view of the invention showing the same in use;

Figure 4 is a sectional view taken substantially on the line 4—4 of Figure 1 and in the direction of the arrows;

Figure 5 is a sectional view taken on the line 5—5 of Figure 2 and in the direction of the arrows;

Figure 6 is a sectional view illustrating a second form of the invention;

Figure 7 is an end view of the invention shown in Figure 6;

Figure 8 is a sectional view taken substantially on the line 8—8 of Figure 6 and in the direction of the arrows;

Figure 9 is a longitudinal sectional view of another form of the invention;

Figure 10 is a longitudinal sectional view taken substantially on the line 10—10 of Figure 9 and in the direction of the arrows;

Figure 11 is a transverse sectional view taken substantially on the line 11—11 of Figure 9 and in the direction of the arrows, and;

Figure 12 is a sectional detail of construction taken on the line 12—12 of Figure 9.

Referring now to the first form of the invention a conventional wagon is illustrated having a bottom 10, sides 12 and 14 respectively and a

2

back 16. Opposed pairs of rails generally indicated at 20 and 22 respectively are supplied on said sides 12 and 14 in order to slidably receive a gate 24 therein. The said back 16 in this form of the invention is supplied with an aperture 26 in order to accommodate the travel of the resilient roller 28. This roller is journaled on a suitable bracket 30 which is in turn secured to a baffle 32.

10 The said baffle may be made in varying widths and heights in order to accommodate the size of wagon on which it is attached. Also secured to the said baffle is a plurality of braces 34, 36, 38 and 40 respectively which are utilized for the purpose of supplying rigidity to a tube 42 and a housing 44. The said housing is detachably secured to the said baffle 32 through the medium of a wing nut and bolt construction generally indicated at 46, which attaches to a suitable angle bracket 48 and a base plate 50. Of course, suitable, conventional bolts may be used wherever it is found desirable and when it is found expedient to otherwise secure elements together such as by welding, this expedient may be resorted to. 15 The said baffle 32 may be made of metal or wood in accordance with the prerogative of the manufacturer and strengthening members may be supplied in accordance with the dictates of sound engineering principles.

20 The said tube 42 has a flexible element 52 extending therethrough, the flexible element being either a rope, cable or the like. One end of the said flexible element has a suitable ring 54 attached thereto. The cable or rope extends through the tube 42 and is entrained about a pulley 56. This pulley is journaled in the said housing 44 and an opening is provided at the lower portion thereof in order to permit the cable or rope to extend therethrough. Then the flexible element terminates in a loop 58 which is secured to a suitable anchor such as the eye bolt 60. This eye bolt may attach to one of the cross members of the wagon which is appurtenant thereto.

25 At the forward end of the said tube 42 there is supplied a guard 62 which is also utilized for the purpose of a hand grip for use in manipulation of the device.

30 It is now readily apparent that by pulling the ring 54 the force is transmitted directly to the baffle 32 thereby urging whatever product is in the wagon therefrom.

35 Referring to Figure 3 the preferred use of the invention is illustrated. Here a conventional tractor 66 is shown having a chain 68 attached

to the drawbar thereof and to the said ring 54. The wagon is in turn anchored to a suitable element through the medium of the tongue 70.

Referring now to Figures 6-8 a second form of the invention is illustrated. Here the conventional wagon is indicated and the differentiating features may be seen in the roller construction. Here a baffle 80 is illustrated with the housing 82 secured on the opposite side thereof. An aperture is formed in the said baffle 80 for reception of the tube 82. Braces 84 and 86 respectively are attached to supports 88 and 90 of the said baffle 80 and also to the said housing 82. An aperture 92 is formed in the lower portion of the said baffle 80 in order to accommodate the passage of the flexible element 94. This flexible element is attached to an eye bolt 96 as is the first form of the invention. It is noted that a pair of rollers 98 and 100 respectively are utilized in this form of the invention, being attached to bearing members or depending brackets 102 and 104 respectively. These bearing members 102 and 104 respectively are attached to the brackets 84 and 86. The operation of this form of the invention is identical to the operation of the first form.

Referring now to Figures 9-12 another form of the invention is illustrated. Here a conventional wagon is shown as a recipient of the invention and the baffle 110 is formed with upper and lower spaced apertures 112 and 114 respectively. A pair of pulleys or sheaves 116 and 118 respectively are journaled in a suitable bracket 120 for accommodation of a flexible element 124. The roller construction in this form of the invention is identical to that roller construction of the second form.

The said flexible element 124 is secured to a pulley housing 126. The said pulley housing 126 is also secured to a bracket 128 which is in turn rigidly attached to the under surface of the said wagon. The said flexible element 124 extends through the lower aperture 114 and is entrained over one of the pulleys. Then, the flexible element returns to the pulley within the pulley housing 126, thence is entrained through the lower aperture against and over the other pulley of the said pair of pulleys. Then, the said flexible element 124 extends through an aperture formed in the endgate 130.

A shield 132 which is substantially triangular in cross section is secured to the said baffle 110 and has a stiffening member 134 extending longitudinally thereof, situated in the apex of the substantially triangular member 132. A hook 136 depends from the stiffening member 134 and has the flexible element 124 entrained therethrough.

The lower portions or legs of the substantially triangular shield 132 are rolled as at 140 and 142 respectively for reducing friction when sliding the shield in removal of the contents of the wagon therefrom. Handles 146 and 148 respectively are attached to the said shield 132 for assistance in actuation of the device.

When ensilage or forage is trapped and blown by the conventional field cutters into a wagon box equipped with the present invention, the wagon is then driven into position at a forage blower. The brakes on the tractor pulling the ensilage or forage wagon are set and then the endgate at the rear of the wagon is opened and the said chain 68 is secured. The tractor pulls the baffle at the desired speed for unloading into a hopper or conveyor 160 to be blown into a silo or other place for proper storage.

By utility of the present invention many man

hours may be saved thereby rendering the use of the present invention economical. Also, the hazards connected with manual unloading of the ensilage are dispensed with and the rate of speed of unloading may be regulated in accordance with the prerogative of the user of the invention.

While there has been described and illustrated but preferred forms of the invention, it is apparent that variations may be made without departing from the spirit thereof. Accordingly, limitation is sought only in accordance with the scope of the following claims.

Having described the invention, what is claimed as new is:

1. An attachment for a wagon having a bottom, sides and a back comprising a baffle, a bracket secured to the rear of said baffle having a roller journaled thereon, said roller rollingly supported on the wagon bottom, and means secured to said bottom and said baffle for slidably actuating said baffle over said bottom, said means including a flexible member secured to the bottom of the wagon, a pulley mounted on said baffle having said flexible member entrained therearound, said roller being spaced farther from said baffle than said pulley to prevent contact of the pulley with said back, and means secured to said baffle forming a longitudinal passage with said flexible element disposed therein for shielding said flexible element, vertical rails secured to said sides, and a vertically movable endgate slidably disposed in said rails.

2. An attachment for a wagon having a bottom, sides and a back comprising a baffle, a bracket secured to said baffle having a roller journaled thereon, said roller rollingly supported on the wagon bottom, and means secured to said bottom and said baffle for slidably actuating said baffle over said bottom, said means including a flexible member secured to the bottom of the wagon, a pulley mounted on said baffle having said flexible member entrained therearound, said roller being secured in advance of said pulley to prevent contact of the pulley with the back of the wagon, and means secured to said baffle for shielding said flexible element, said shielding means comprising a tube, and a stop carried by said tube reacting on said wagon to hold said tube in a fixed position.

3. An attachment for a wagon having a bottom, sides and a back comprising a baffle, a bracket secured to said baffle having a roller journaled thereon, said roller rollingly supported on the wagon bottom, and means secured to said bottom and said baffle for slidably actuating said baffle over said bottom, said means including a flexible member secured to the bottom of the wagon, a pulley mounted on said baffle having said flexible member entrained therearound, and means secured to said baffle for shielding said flexible element, said shielding means comprising a housing secured to said baffle, and a guide secured to said housing having said flexible member extending therethrough.

4. An attachment for wagons having a bottom, sides, a back and an open front, comprising an angularly disposed baffle disposed between said sides, a housing secured to the rear surface of said baffle and having a pulley rotatively mounted therein, braces secured to said housing and said baffle, brackets fixed to said braces and having rollers mounted thereon, a tube fixed to said baffle and having a flexible member passed therethrough with one end of said flexible member adapted to be fixed to a pulling member, and

the other end of said flexible member being fixed to said wagon, said rollers being disposed in advance of said pulley housing so that said rollers contact said wagon back preventing contact of the pulley housing with the wagon back, and an endgate fixed to the open end of said wagon and a guard fixed to said tube to contact said endgate when said endgate is in the closed position thereby preventing longitudinal movement of said tube and said baffle when said endgate is closed.

5. A wagon attachment comprising a baffle having a bracket fixed thereto, a roller carried by said bracket and adapted to rotatively mount the baffle in the wagon, a housing having a pulley therein fixed to said baffle, a tube fixed at one end of said baffle and having a flexible member passed therethrough, said wagon including a vertically slidable endgate, the opposite end of said tube having a guard fixed thereto for engagement with said endgate when it is in the

closed position to prevent substantial movement of said tube and said baffle in the wagon when the endgate is in the closed position, and said flexible member extending through the endgate opening at one end and having the other end fixed to the wagon.
